Primary Examiner — Philip S Hyder(74) *Attorney, Agent, or Firm* — Thompson Hine LLP(57) **CLAIM**

The ornamental design for an emergency hammer with guard, as shown and described.

DESCRIPTION

FIG. 1 is a perspective view of a new design for an emergency hammer with guard;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines depict aspects of the emergency hammer with guard in which the design is embodied that are not considered part of the claimed design.
